UNITED STATES PATENT OFFICE.

CALAWAY HERNDON, OF WAGONER, OKLAHOMA.

RAIL-JOINT.

1,103,964.

Specification of Letters Patent. Patented July 21, 1914.

Application filed April 22, 1913. Serial No. 762,878.

To all whom it may concern:

Be it known that I, CALAWAY HERNDON, a citizen of the United States, residing at Wagoner, in the county of Wagoner and State of Oklahoma, have invented a new and useful Rail-Joint, of which the following is a specification.

The invention relates to improvements in rail joints.

10 The object of the present invention is to improve the construction of rail joints, and to provide a simple, practical and inexpensive rail joint chain of strong and durable construction, capable of securely holding the 15 rails, and of permitting free expansion and contraction of the same.

A further object of the invention is to provide a rail joint chain of this character capable of gripping the opposite sides of 20 the rails beneath the head and at the base, and adapted to be adjusted to take up the wear of the parts, and capable also of operating as a spring lock for retaining the nuts against rotary movement on the bolts.

25 The invention also has for its object to provide a rail joint chain, adapted to be employed as a temporary joint for repairing broken rails, and equipped with spike receiving openings arranged to permit the 30 heads of the spike to engage both the bottom portion of the chair and the bottom flanges of the rails and having outer end walls for supporting or holding the spike against movement laterally of the rails, whereby 35 spreading of the rails is effectually prevented.

With these and other objects in view, the invention consists in the construction and novel combination of parts hereinafter fully 40 described, illustrated in the accompanying drawing, and pointed out in the claim here-to appended; it being understood that various changes in the form, proportion, size and minor details of construction, within 45 the scope of the claim, may be resorted to without departing from the spirit or sacrificing any of the advantages of the invention.

In the drawing: Figure 1 is a perspective view of a rail joint, constructed in accordance with this invention. Fig. 2 is a horizontal sectional view of the same. Fig. 3 is a transverse sectional view, taken on the line 3-3 of Fig. 2 and illustrating the arrangement of the inner and outer spikes.

50 Like numerals of reference designate cor-

responding parts in all the figures of the drawing.

In the accompanying drawing in which is illustrated the preferred embodiment of the invention, the rail joint chair, which consists of a single piece of metal, is of substantially uniform thickness and is composed of a horizontal bottom plate 1 and integral sides 2 of angular formation and consisting of inclined lower portions 3 and substantially vertical upper portions 4. The horizontal bottom plate 1 presents flat upper and lower faces to cross ties 5, and bottom flanges 6 of rails 7. The lower inclined portions 3 of the sides of the chair extend upwardly and inwardly and fit against the upper faces of the side flanges 6, and the upper vertical portions 4 extend upwardly from the inclined lower portions 3 and fit against the underside of the head of the rails, as clearly illustrated in Fig. 3 of the drawing. By this construction, the rails are firmly engaged beneath the head and at the base and are securely clamped by the chair. The upper portions 4 are provided at their inner faces with longitudinal grooves or recesses 8, forming upper and lower longitudinal ribs or projecting portions 9 and 10, which are arranged in spaced relation with the web of the rail, whereby when the engaging portions of the sides of the chair become worn through the vibration incident to the travel of trains over the rail joint, the wear may be taken up by drawing the sides inwardly toward the web by transverse bolts 11. The bolts 11, which are provided with nuts 12, extend through registering openings 13 in the sides of the chair and also pass through enlarged openings 14 in the webs of the rails. The openings 14 are of sufficient size to permit the free expansion and contraction of the rails due to changes in temperature. The sides of the rail joint have sufficient resiliency to enable them to be sprung inwardly by the bolts and nuts, and they are adapted to exert a spring action on the same to maintain them in tight frictional engagement with the bolts and the nuts to prevent the same from being loosened through the vibration of the rail joint.

The chair is secured to the cross ties 5 by inner and outer spikes 15 and 16, arranged in inner and outer openings 17 and 18 in the bottom portion of the rail chair. The inner openings, which extend through the lower

inclined portions 3 and the bottom portion 1 of the chair, have enlarged upper portions 19, formed in the sides of the chair and extending inwardly transversely of the rail 5 joint and being of sufficient size to permit the heads of the inner spikes to directly engage the bottom flanges 6 of the rails, as clearly illustrated at the right hand side of Fig. 3 of the drawing. The enlarged upper 10 portions 19 of the inner openings form recesses in the inclined portions 3 of the sides of the chair and expose the side edges of the bottom flanges of the rails thereat. The inner spikes are supported and maintained 15 in engagement with the bottom flanges of the rails by the outer end walls of the inner openings, the said outer end walls being formed by the bottom plate 1 and preventing outward movement of the inner spikes 20 in a direction laterally of the rails and preventing spreading of the said rails. The inner openings 17 also present side walls to the spikes and by forming enlarged openings in the inclined portions of the sides of the chair 25 to permit the heads of the spikes to engage the bottom flanges of the rails, the spikes are permitted to sink deeper into the cross ties and their holding power is thereby increased. Also by terminating the inner 30 openings short of the marginal projecting portions of the bottom, the outer end walls of the said inner openings extend from the upper faces of the inclined portions of the sides to the lower faces of the bottom of the 35 chair. The openings 18 for the outer spikes are spaced from the bottom flanges of the rails and are formed in the projecting marginal portions of the bottom of the chair. The outer marginal portions form horizontal 40 longitudinal flanges, which are arranged in the same plane as the intermediate portion of the said bottom of the chair, and the heads of the spikes 16 engage the rail chair, the spikes being supported and maintained 45 in such engagement by the outer end walls of the opening 18, as clearly illustrated at the left hand side of Fig. 3 of the drawing. The outer end walls of the openings 18 pre-

vent movement of the outer spikes in a direction transversely of the rails.

50

The inner and outer spikes securely fasten the rails to the cross ties and enable the chair to be advantageously employed as a temporary rail joint for repairing broken rails, and it will securely hold the ends of the same 55 without the aid of the transverse bolts 11. In assembling the parts, the rail joint is slipped on the end of one of the rails and moved longitudinally thereof to permit the ends of the rails to be brought together, and 60 it is then moved longitudinally to engage it with the other rail, the ends of the rails being located centrally of the chair.

55

What is claimed is:—

In a rail joint, the combination with rails, 65 of a chair consisting of a single piece and comprising a bottom plate and integral sides composed of inclined lower portions, the bottom plate being extended laterally beyond the sides to form projecting flanges, 70 and the said chair being provided with inner and outer spike receiving openings, the inner openings extending through the inclined portions of the sides and the bottom plate at the side edges of the rails and having transversely enlarged upper portions forming recesses in the inclined portions of the sides, so as to expose the side flanges of the rails to 75 permit the heads of the spikes to directly engage the rails, thereby enabling the spikes to sink deeper into the cross ties and presenting side and outer end walls to the spikes, the outer end walls extending from the upper faces of the said inclined portions to the lower face of the bottom plate, and the said 80 outer openings being formed in the laterally projecting side flanges of the bottom plate and presenting side and outer end walls to the spikes.

75

In testimony that I claim the foregoing as 90 my own, I have hereto affixed my signature in the presence of two witnesses.

CALAWAY HERNDON.
